ELEVATOR

Stanley M. Mercier, Bexley, Ohio, assignor, by
mesne assignments, to The Jeffrey Manufacturing Company, a corporation of Ohio

Application September 1, 1943, Serial No. 500,799

10 Claims. (Cl. 198—140)

1

This invention relates to an elevator or conveyor which is constructed particularly for the elevation of hot material such as hot clay used in the cracking of petroleum.

An object of the invention is to provide an elevator or conveyor of great height which has a frame structure formed independently of the housing or casing which substantially totally encloses the elevating or conveying mechanism.

A further object of the invention is to provide a conveyor of the above mentioned type in which the housing or casing is formed largely if not totally of insulating walls, within an exterior supporting structure.

A further object of the invention is to provide a conveyor casing or housing of the above mentioned type in which the walls are formed of separable panels independently suspended from the main frame and also preferably mounted for lateral and vertical or upright expansion with respect to said main frame.

A further object of the invention is to provide an improved conveyor housing including a main frame having spaced upright corner members rigidly connected at spaced horizontal planes by belts each of which includes four plates opposite plates of which connect the upright corner members and opposite plates of which are spaced inwardly of the corner members and connected at opposite ends to the first pair of plates thereby forming spaced circumferential belts adapted to support tubular sections of the conveyor housing between and spaced from the upright corner members.

A further object of the invention is to provide an improved conveyor mechanism including a main frame having a conveyor mechanism operating therein and a housing associated therewith for enclosing a conveyor mechanism, the housing including a plurality of separate insulated panels and separate aligned conveyor guide means associated with separate of said panels for guiding the conveyor mechanism, said guides being mounted to provide for relative movement of the guides and panels in response to expansion and contraction thereof.

Other objects of the invention will appear hereinafter, the novel features and combinations being set forth in the appended claims.

In the accompanying drawings:

Fig. 1 is a side elevational view of an elevator or conveyor incorporating the features of my invention;

Fig. 2 is a view of the head portion of the conveyor taken on the line 2—2 of Fig. 1, looking in the direction of the arrows;

Fig. 3 is a transverse sectional view of the conveyor, the view being taken on line 3—3 of Fig. 1;

Fig. 4 is an enlarged detailed sectional view

showing certain details of the top ventilating door of the conveyor housing;

Fig. 5 is an enlarged detailed view showing a detail of the bottom ventilating door of the conveyor housing;

Fig. 6 is an enlarged sectional elevational view through the axis of the foot shaft of the conveyor showing one end of said foot shaft and associated structure;

Fig. 7 is a transverse sectional view showing one end of the head shaft and head sprocket of the elevator or conveyor;

Fig. 8 is a view of a tooth of the head sprocket and associated parts;

Fig. 9 is an elevational view of one of the wheels of the foot shaft, part of the wheel being broken away;

Fig. 10 is a sectional plan view showing one end of the foot shaft and associated apparatus, the view being taken substantially at right angles to the view of Fig. 6, no attempt being made in this Fig. 10 to show the foot wheel and associated insulating material;

Fig. 11 is an end view of the bearing housing for the head shaft with the housing cap removed, the view being taken on line 11—11 of Fig. 7, looking in the direction of the arrows;

Fig. 12 is an enlarged side view of a portion of one side of the main frame of the elevator showing the attaching bolts for attaching removable panels of the conveyor housing or casing;

Fig. 13 is a sectional view taken on the line 13—13 of Fig. 12, looking in the direction of the arrows;

Fig. 14 is a sectional view taken on the line 14—14 of Fig. 12, looking in the direction of the arrows;

Figs. 15 and 16 are enlarged sectional elevational views showing modified forms of mechanism for attaching sectional guides for the conveyor chain to the adjacent panels of the conveyor housing or casing;

Fig. 17 is an enlarged sectional view showing particularly an auxiliary discharge chute for guiding material from the conveyor buckets to the main discharge chute;

Fig. 18 is a transverse sectional view of the conveyor taken on line 18—18 of Fig. 1; and

Fig. 19 is a sectional view taken on line 19—19 of Fig. 2.

The elevator or conveyor of my invention is illustrated as of the bucket type and this is the preferred form, though it is evident that many features thereof are adaptable to other types of conveyors and elevators and certain features while designed particularly for my elevator and conveyor may find use in other fields where related problems are found.

It may be stated that the invention has solved

a number of problems most of which have been created by virtue of the specific task for which the elevator or conveyor was designed to perform. To understand the reasons which present the numerous problems I have solved it may be mentioned that in one installation involving my invention the elevator or conveyor has a height of approximately 175 feet. Furthermore, this elevator or conveyor is not contained within a building but is exposed to all of the elements including particularly rain and wind. A still further complication which presented problems was the fact that the elevator or conveyor above mentioned was designed particularly to elevate hot material such as hot fuller's earth which was used as a catalyst in a process for cracking petroleum to produce a high octane fuel or gasoline. For example, in this one installation the temperature inside the casing at times approximates 1000 degrees Fahrenheit and it is an interesting fact that because of the great height of the elevator and the high temperature differential between the inside and outside, there are times when the temperatures on one side of the conveyor are considerably higher than on the other side, depending on the direction of the wind. The conveyor, therefore, not only has to compensate for differences between its operating temperature and the ambient temperatures but the mere force of the wind itself becomes a factor in a device of this height, considering its proportionally small base.

As above indicated, while many of the features have been designed to overcome problems peculiar to the conditions above mentioned, it is evident that some of them have a much wider range and use.

Referring to the particular structure of the conveyor of my invention, said conveyor comprises a vertical or upwardly extending tower or main frame 20 which main frame 20, as viewed in cross section in Figs. 3 and 18 of the drawings, is rectangular in shape and each of the four corners includes a vertical or upright structural member such as a channel 21. Each of the channels 21 in the finally assembled condition of the main frame 20 constitutes a continuous upright member which extends from the foot or bottom of the main frame 20 to the top thereof. It is to be understood that these continuous channels 21 may be built up of individual channel members rigidly connected together in any desired manner. At their bottoms the channels 21 are provided with feet 22 preferably rigidly attached to base members which may, for example, be mounted on a poured concrete base sunk sufficiently in the ground to provide a firm foundation. At their tops the channel members 21 are rigidly connected together by side I-beams 23 and cross channels 24, all of said structural members 21, 23 and 24 being rigidly connected together. Along the sides, each of the two front and rear channel members 21 are connected by one or more diagonal braces 25 as well as by horizontal angle braces 26. On the same plane with each of the angle braces 26 and on the back and front of the main frame or tower 20, I provide moment connections in the form of horizontal plates 27 each rigidly connected at its opposite ends to a pair of channels 21, (see Figs. 18 and 19) said horizontal plates 27 being provided with a pair of spaced horizontal stiffeners 28 so as to increase their rigidity. This particular frame construction makes it possible to remove individual panels of the casing or housing of the

conveyor, as described more completely hereinafter.

It may be pointed out that the plates 27 are preferably vertically spaced a uniform distance apart and in one installation this distance is eight feet. It is evident, however, that the foot and head sections of the conveyor are of special and different construction. The main frame or tower of the conveyor is an independent self-supporting structural unit and in fact it acts as an outside support for a sectional housing or casing and cooperates therewith to form a complete housing structure connecting the head and foot sections of the conveyor, as hereinafter described more completely. Furthermore, this main frame or tower is entirely outside the elevator casing and removed from the influence of high temperature within said casing and thus free from major thermal stresses and strains.

Mounted upon the I-beams 23 at the top of the main frame 20 is a pair of spaced bearing boxes 29, the structure of which is disclosed in detail in Fig. 7 of the drawings and which is described hereinafter. At this time it may be pointed out that the bearing boxes 29 support a horizontally extending head shaft 30 which carries a head support assembly 31, which is also described in detail hereinafter. For the moment it may be pointed out that the head support 31 includes a pair of sprocket wheels 32 which operate with and drive a pair of spaced endless chains 33 of a bucket elevator or conveyor mechanism 34.

Extending between the two chains 33 and carried thereby is a plurality of buckets 35, said buckets 35 being rigidly attached adjacent their sides to the inner side bars of the chains 33 by appropriate brackets or attachments 36 (see Fig. 6).

At the foot or bottom of the tower or main frame 20 there is a foot shaft 37 which is disclosed in detail in Fig. 6 of the drawings and which is described more completely hereinafter. For the moment it may be pointed out that the foot shaft 37 carries a foot shaft assembly 38 including a pair of spaced traction wheels 39 which receive the two endless chains 33.

One of the important features of my invention is the provision of a totally enclosing housing or casing 40 which has a number of distinctive characteristics. In the first place, this housing or casing 40 is insulated in view of the fact that the internal temperature thereof may become very high and in one installation a temperature of 1000 degrees Fahrenheit was encountered. The main frame 20 is not subject to this high temperature as it is outside the casing and is thus free of heat stresses.

Another characteristic is that the casing is in no sense a main frame for the elevator or conveyor as is usually the case where an enclosing casing or housing is provided. Furthermore, the casing is made up of individual panels and each panel is mounted for expansion both vertically and laterally with respect to the main frame 20. The casing or housing 40 includes three principal parts or sections which are the head section, foot section and a plurality of intermediate sections. The head section is generally designated by the reference character 41, this being the part of the casing or housing associated with the head sprocket assembly 31. This head part 41 merely comprises a totally enclosing hood made up of top, front, back and side plates, all rigidly connected together and reinforced by appropriate

angle members and in which the interior thereof is lined with a plastic insulating material, the insulating material being attached to a metal casing forming this section or part by appropriate studs, the heads of which are molded into the insulating material.

The head section or part of casing 41 also includes a main discharge spout or chute 42. It may be pointed out that one of the features of my invention, which is illustrated particularly in Fig. 17 of the drawings, involves this main discharge spout or chute 42. It is desirable to prevent as little carry over of material as possible or, in other words, to effect as nearly as possible a complete discharge of the material as the buckets go over the head sprocket assembly 31 and discharge the material onto the chute 42. At the same time, if this were attempted to be done by placing the upper edge of the discharge chute 42 quite close to the path of travel of the lower edge of each bucket 35 it is possible that during operation the said bucket edges might hit the chute edge and cause damage to one or both. To produce the desired result, yet to overcome the possibility of any damage, I provide an auxiliary chute 43 (see Fig. 17) which extends the full width of the main chute 42 and is pivotally attached thereto on a horizontal axis at a point such that the bottom of said auxiliary chute will normally rest on the main chute 42 while the top edge thereof is closely adjacent the path of travel of the foremost edge of each bucket 35. As a consequence of this structure, there is a minimum carry over of material from the working run to the return run of the conveyor mechanism 34 and should the forward edge of any bucket 35 strike the upper edge of the auxiliary chute 43, said chute 43 is free to pivot about its horizontal axis provided by pivot bolts 44 so as to prevent any damage either to the bucket or auxiliary chute 43. Since the pivotal axis of chute 43 is to the right of its center of gravity, as viewed in Fig. 17, it is evident that the left hand end thereof will automatically move downwardly and restore the auxiliary chute 43 to its normal position, as illustrated in Fig. 17 of the drawings, as soon as it is released by the passing of a bucket 35 which has contacted it. The discharge chute or spout 42 above described is claimed in my Patent No. 2,400,246, dated May 14, 1946, entitled "Conveyor."

Another feature of the head part or section of casing 41 is a sliding door 45 which is illustrated more in detail in Fig. 4 of the drawings. The door 45 is constructed to slide in spaced clamping guide means 46 which, when released, permits lateral sliding thereof and which may be clamped so as to clamp the door 45 rigidly in place. The function of the door 45 is primarily to provide a top ventilator so that when it is open the hot gases or hot air within the casing or housing 40 may be vented and thus the interior thereof cooled. This may be desirable, particularly when the machine is shut down for repairs.

At the other end of the housing or casing 40 there is a foot part or section 47 and this foot section involves a number of important details of construction. In the first place, the foot section includes a feed chute 48 by which hot clay or other material to be elevated is delivered preferably directly into the buckets 35 at the bottom of the feed run of the conveyor mechanism 34. Furthermore, the foot section or part 47 includes structure providing a gastight dust and heat seal for the foot shaft 37 which is mounted for sub-

stantially free vertical movement through a limited range so as to compensate for changes in the lengths of the chains 33, particularly under the influence of temperature changes. Furthermore, it may be pointed out that the main frame 20 adjacent the foot section 47 is provided with considerable auxiliary equipment, as hereinafter described more completely.

Adjacent the bottom and rear of the foot section 47 there is a draft or air inlet door 49, shown in some detail in Fig. 5 of the drawings, which when opened provides an inlet for the air to cool the housing or casing 40, as above mentioned. In other words, the two doors 45 and 49 will be simultaneously opened to cool the casing or housing 40 and when it is desired to enclose said housing or casing 40 these two doors will be closed. Adjacent the door 49 the casing is not insulated because this is below the position where the hot material is present. The door 49 is preferably of the sliding type and is provided with clamping guide means quite similar to the guide means 46 provided for door 45.

Attention is now directed to Figs. 1, 6 and 10 of the drawings and to the structure of the foot part or section 47 of casing 40 and associated apparatus which provides the gastight heat and dust seal while providing for floating vertical movement of the foot shaft 37.

Referring particularly to Figs. 6 and 10 of the drawings which illustrate structure which is duplicated on each side of the elevator, it will be seen that the housing or casing 40 in this section includes a steel or metal side plate 50 which is attached to the adjacent portion of the main frame or tower 20. Rigidly attached to the side plate 50 and forming the lining of this portion of the casing or housing 40 is a heavy plate of insulating material 51 which is the same in texture as the insulating material used throughout most of the casing 40 to provide the insulating lining thereof and is preferably in the form of a molded insulating material having high insulation characteristics. The metal plate 50 and the insulating material 51 are provided with a vertical elongated slot 52 which is provided with a metal frame 53, rigidly attached to the plate 50 as by welding. The foot shaft 37 extends through the slot 52 and frame 53 and is mounted to move freely in a vertical direction therein. On the outside of the plate 50 and adjacent the slot 52 is a stationary box structure 54 which is formed by a pair of spaced vertical angle members 55 (see Fig. 10) which are rigidly attached to the plate 50 by appropriate bolts. Riveted to the angle members 55 and extending across the outer free ends thereof is a U-shaped cover plate 56. Both the top and bottom of the cover plate 56 are provided with angle members which extend between the upright angle members 55 and are rigidly connected thereto as well as to the plate 50 and the cover plate 56. The bottom of these angle members is seen at 57 in Fig. 6 of the drawings. It is thus seen that the angle members 55 and 57 and the U-shaped cover plate 56 cooperate to provide an enclosing stationary box adjacent the slot 52 and this stationary box is provided with an elongated slot similar to the slot 52 which is defined by a border frame member 58, which frame member 58 is rigidly attached thereto as by screws and includes a central elongated slot 59, which slot 59 is somewhat wider than the slot 52.

Mounted on the foot shaft 37 to move upwardly and downwardly therewith while at the

same time providing for free rotation of shaft 37 with respect thereto, is a rectangular plate 60 of insulating material, similar to the material 51, which is rigidly attached to a shiftable steel or metal plate 61 which has a rigidly attached frame 62 which frames the insulation plate 60 and helps to hold it rigid with the steel plate 61. The composite shiftable plate 60-61 is mounted for sliding movement within the afore-described box formed by angle members 55 and 57 and cover plate 56. In cooperation with the side plate 50 means are provided so as to effect a substantially continuous insulating wall to seal the slot 52 for all positions of adjustment of the shaft 37. To this end the inner periphery of the frame member 53 is provided with a continuous groove which carries and supports a pair of continuous strips of gasket material 63 against which the steel plate 61 continuously bears and has a sliding relation, thus providing an effective seal along this line of contact while permitting free sliding movement of the composite plate 60-61.

Furthermore, the steel plate 61 extends around its entire periphery beyond the insulation plate 60 and the frame 62 and provides abutment or bearing areas for a plurality of coil springs 64 which are received by spaced guide posts 65 welded to a floating rectangular frame 66 made from an angle member which is bent or otherwise formed in a rectangle. The bottom of said frame 66 has frictional sliding contact with the side plate 50, the outwardly extending flange of which overlaps the frame 62 so that as the composite plate 60-61 moves up and down, it will carry the floating frame 66 held in frictional contact with the side plate 50. The overlapping flange of the frame 66 has a relatively close fit with the frame 62 so as to provide an effective seal therewith, though there is sufficient clearance between the two to provide for their relative movement along a horizontal axis. It is therefore seen that there is a double seal between the slot 52 and the atmosphere, one seal being provided by the cooperation of floating frame 66 with the side plate 50 and with the frame 62, the other seal being provided by the insulating strip 63 in cooperation with the steel plate 61.

The apparatus which provides the gas-tight heat and dust seal above described is claimed in my Patent No. 2,384,189, dated Sept. 4, 1945, entitled "Elevator."

Between the head and foot sections or parts of the casing 40 is a plurality of intermediate sections 67 which are of generally similar construction and which form the principal portion of the casing insofar as actual height is concerned. In one installation involving my invention these intermediate sections 67 are made in eight foot lengths, though the section may have any desired length.

The structure of a typical intermediate section 67 is illustrated in Figs. 1, 3, 12, 13 and 14 of the drawings. As above mentioned, the plates 27 are on the front and back of the main frame 20 and constitute a part thereof. Along the sides of the main frame and also constituting a part thereof are the mentioned horizontal braces 26. Spaced inwardly from the angle braces 26 and extending between and rigidly attached at their ends to the plates 27 are spaced plates 70 (see Fig. 13) which are the same width as the plates 27 and are provided with spaced stiffeners 71 and which with the plates 27 and stiffeners 28 cooperate to pro-

vide a circumferential belt around the entire conveyor 34 and, of course, form an integral part of said frame 20. There is such a belt every eight feet.

Attached to each plate 70 is a slab or plate of insulating material 68 similar to the above described material 51 which has a plurality of embedded bolts which are attached to said plate 70 by nuts and washers 69 (see Figs. 12 and 13) which is typical of the attaching means for all insulating material and associated steel or metal plates. There is a band or ring of insulating panel or material formed of four separate slabs extending around the inside of each of the described belts and the plate or slab 68 is one of these separate slabs. Each of the plates 27 and 70 supports a panel of the intermediate section 67 of said casing 40. As previously indicated there is a belt formed by the aforescribed plates 27 and 70 and associated stiffeners 28 and 71, respectively, spaced at approximately every eight foot increment in height of the elevator and each side of the elevator is made up of panels suspended from said plates 27 and 70.

As clearly illustrated in Fig. 3 of the drawings, there are front and rear panels 72 and there are two side panels 73. The front and rear panels 72 are suspended from the plate 27 and the two side panels 73 are suspended from the plates 70. The front and rear panels 72 are mounted to be readily removable and this is the purpose of the aforescribed moment connections formed by said plates 27 and stiffeners 28. The side panels 73 are not intended to be readily removable though, if desired, one of them may be made up of sections, as illustrated for the center panel in Fig. 1 of the drawings, so as to be removable by section. Generally the panels 72 and 73 are of similar construction and each consists merely of an outer steel or metal plate such as plate 74 (see Fig. 13) to which a plate or block of insulating material 75 is rigidly attached, the insulating material 75 being similar to the aforescribed insulating material 68 and being attached to the plate 74 in the manner that insulating material 68 is attached to plate 70. In other words, the individual panels forming the sides of the housing are a composite structure having an outer steel or metal surface with a liner of insulating material.

It is obvious that when the several panels of the housing 40 are assembled their adjacent end edges lie substantially in the same planes and that they cooperate with the fixed belt members 55 formed by plates 27 and 70 and their attached insulating material to provide tubular sections of a totally enclosing insulating housing, it being understood that substantially the entire interior of the casing or housing 40 from the insulating bottom 76 (see Fig. 6) to the cover 41 has a fully insulated surface and this even extends to the feed chute 49 and the discharge chute 42, the interiors of which are lined with insulating material.

The manner in which a panel 72 and similarly a panel 73 is attached to a plate 27 or 70 of one of the main frame belts is disclosed particularly in Figs. 12 and 13 of the drawings, to which attention is now directed.

In Fig. 12 of the drawings, the vertical line 77 designates the center line of two adjacent panels 73, one of which is above and the other below a plate 70 of one of the aforementioned belts.

These Figures 12 and 13 illustrate the manner

of attaching both the tops and the bottoms of the sections or panels 73 to a plate 70.

As clearly illustrated in Fig. 13 of the drawings, the metal plate 74 in the bottom of this figure extends upwardly beyond the upper extension of the insulating material 75 which abuts the bottom of insulation 68. This upwardly extending portion of plate 74 overlaps the bottom portion of plate 70 and a plurality of bolts 78 provided with nuts and washers extend through aligned holes in the plates 70 and 74, clamping them together.

Attention is directed particularly to Fig. 12 of the drawings and to an important feature of my invention. It is to be noted that the bolt 78 which is on the center line 77 substantially fills the two aligned holes in the plates 70 and 74, thus making a tight fit in said hole. The next adjacent bolt 78 both to the right and to the left of the center line 77 is of similar construction. As a consequence adjacent the center portion of the panel 73 there are three bolts which substantially fill cooperating holes in plates 70 and 74 through which they extend and which rigidly attach each of these two plates together in local areas thereof. There are a number of additional bolts 78 through aligned holes in the plates 70 and 74 both to the right and to the left of the above-mentioned three bolts 78 and these additional bolts 78 are smaller than the aligned holes in the plates 70 and 74. As a consequence of this construction, lateral expansion between the two plates 70 and 74 is provided for which may be extremely desirable under the variety of temperature conditions to which the casing 40 is subjected.

Each of the panels 72 and 73 is suspended at its top from a plate 27 or 70 in a similar manner to provide for vertical upright or longitudinal expansion of each panel 72 or 73. The lower end of each plate 74, which is illustrated in the top portion of Figs. 12 and 13 of the drawings, overlaps the upper end of the associated plate 70 and is attached thereto by a plurality of bolts 79, provided with nuts and washers. To allow for expansion of these panels, the bolts 79 do not fill the holes in plates 70 and 74 through which they extend, thus allowing relative movement between the plates 70 and 74. The upper and lower edges of plates 74 of panels 72 are secured to the belt plates 27 in a manner identical to that just described in connection with the plates 74 of panels 73 and belt plates 70 thus allowing relative movement of the panels 72 and 73 with respect to the main frame 20 and the belts, of which plates 27 and 70 are a part. The front and rear panels 72 and the side panels 73 are interconnected at their side edges (see Fig. 3) by bolts and washers in a manner similar to that by which the lower edges of the panels are connected to the members 70.

As previously mentioned, insulation 68 is attached to plate 70 by embedded bolts and cooperating nuts and washers 69. A similar row of embedded bolts with cooperating nuts and washers 81 attaches the top of insulating slab or material 75 to the plate 74. Furthermore, as illustrated in Figs. 12 and 13 of the drawings, there is an additional row of embedded bolts provided with cooperating nuts and washers 82, which bolts are embedded in the top of insulating material 68 and which extend through holes adjacent the bottom of plate 74 of panel 73; thus attaching said plate 74 to the insulating slab 68. Since relative movement may occur between plate 75

74 and slab 68, the holes through which the bolts extend which are provided with nuts and washers 82, are larger than the bolts. It may further be mentioned that lateral reinforcing bars 83 are provided across the tops and bottoms of the plates 74, thus providing lateral reinforcing means for the panels 73. Similar reinforcing means may be provided for the tops and bottoms of the panels 72.

10 As seen in Fig. 2 of the drawings the panels 72 are preferably provided with continuous rectangular frame members 84 which are rigidly attached to the steel plates thereof and extend inwardly along the top, bottom and side edges of the insulating material forming the lining of said panels 72. It is thus seen that both lateral and vertical expansion of the panels 72 and 73 of the casing or housing 40 are provided.

15 It will also be seen that each intermediate section 67 of the elevator includes a tubular casing section formed of panels 72 and 73 and that each of these tubular sections is suspended from one of the horizontal circumferential belts formed by the plates 27 and 70. The bottom of 20 each tubular section is slidably interconnected with the top of an adjacent tubular section as described. From the foregoing description it is 25 obvious that the moment members 27 rigidly connect corner members 21 of the main frame 20 and that the members 70 rigidly connect the moment members and thus form parts of the main frame 20. In addition to forming parts of the main frame these members, which form the circumferential belts, also form parts of the conveyor housing and each is provided with a slab of insulation which forms a section of an inner surface of the housing or casing.

30 To provide guides for the chains 33 which in no way interfere with the free expansion of the side panels 73, I provide sectional trough-like members 80, there being two such guide members 80 on each of the panels 73, one for the working run and one for the return run of each chain 33. The upper end of each guide 80 has a pair of horizontal reinforcing webs 85 along the sides of the U-shaped guide trough 80 which have an effective continuation across the back of the trough member 80 by virtue of a plate 86 which is welded thereto. The plate 86 rests on top of the insulating slab 75. A pair of clamping bolts 87, which extend through a large opening in the insulation 75 and a hole in the plate 74 and through an open bottom slot in a downwardly extending portion of web 85, clamps the upper end of the guide member 80 to the panel 73.

35 As illustrated in Fig. 13 of the drawings, there is a spool type spacer 88 between the downwardly extending portion of web 85 and an insulating plate 89. Said plate 89 abuts plate 74 and is received in a recess adjacent the top of the insulation 75. A washer 90 of insulating material is provided outside the plate 74 for the clamping bolt 87. Adjacent the bottom of each guide 80 there is a similar pair of clamping bolts 91 and associated structure. It is to be noted, however, 40 that there is a space seen at 92 between the top of the insulation 68 and a plate 86 which is similar in structure to the aforescribed plate 86, thus providing for the above described relative movement between the panel 73 and the insulation 68. To remove one of the guides 80 the bolts 87 and 91 are loosened and removable blocks 93 and 93' of insulating material in recesses directly above the plates 86 and 86', respectively, are 45 removed, permitting the guide 80 to be lifted vertically.

tically and slid off the clamping washer associated with bolts 87 and 91. It may further be pointed out that guides for locating and aligning the guide members 80 are provided in the form of inwardly extending top and bottom bars 94 and 94' which receive notches in the plates 86 and 86', respectively. The bars 94 and 94' are rigidly attached to the plate 74 as by welding.

In Fig. 15 of the drawings, I have illustrated a modified form of attaching means in which a cast thimble 95 surrounds the bolt 87' and extends through an insulating plate 89' which is adjacent the steel plate 74.

In Fig. 16 of the drawings, I have illustrated a further modification of attaching means for the guide 80 which permits the removal thereof without requiring it to be lifted vertically and in this case the structure is similar to that of Fig. 15 except that a bolt 87" is provided with a cotter pin 96 which holds a washer 97 in place and the vertical portion of web 85, instead of being slotted and thus open at the bottom as it is in the modification of Figs. 13 and 15, is merely provided with a round opening which receives a reduced portion of the thimble 95'. It is evident that by removing the cotter pin 96 and the washer 97 the guide plate 86 may be moved horizontally without requiring any vertical movement as is required in the structures of Figs. 13 and 15.

Attention is now directed particularly to Fig. 7 of the drawings which illustrates one end of the head sprocket assembly 31, one of the bearing boxes 29 and certain associated apparatus, it being understood that the structure is duplicated on the other side of the elevator except for differences which are hereinafter pointed out.

Mounted in spaced relation on the head shaft 30 are the head or drive sprockets 32, there being one for each of the chains 33, as previously pointed out, said sprockets 32 preferably being of similar construction. Each sprocket 32 includes a plate steel center ring 98 preferably keyed and welded to the shaft 30. The additional diameter of the wheel 32 is formed by a pair of concentric rings 99 and 100, the first being shrunk onto the center ring 98 and the second being in turn shrunk onto the ring 99. In building up this wheel, the ring 99 is heated to a high temperature so that it can be forced or slipped onto the ring 98 and when it cools to atmospheric temperature it will be under tension. Thereafter, the edges of the rings 98 and 99 are preferably welded together by welds 101 which may be either continuous or at spaced intervals along the periphery thereof. In a similar manner the ring 100 is shrunk on the ring 99 and attached thereto by welds 102 similar to the welds 101. The ring 100 is also under tension at atmospheric temperature.

As a consequence of the above structure, the wheel 32 can expand or contract with variations in temperature without causing damage thereto and at the same time the structure is such that the parts are held together both by friction and by welded connections. Since shaft 30 is cooled, as hereinafter described, the temperature of the wheel rim of possibly 1000 degrees F. will be much higher than the shaft temperature during operation of the conveyor. This wheel and shaft construction is disclosed and claimed in my application, Serial No. 607,115, filed July 26, 1945, entitled Elevator.

Mounted on the outer periphery of the ring 100 is a plurality of removable sprocket teeth

103 and the bottom or root of each tooth 103 is provided with an arcuate groove which receives the periphery of the ring 100, said root of tooth 103 being bifurcated so that a portion or part thereof extends on each side of the ring 100. The final attachment between each tooth 103 and the ring 100 is by virtue of a pair of pins 104 which have a pressed fit with aligned holes in the ring 100 and the root of tooth 103, the pins 104 preferably being welded at one or two spots to the root of tooth 103 after the parts are assembled. To remove a tooth 103 the welded spot is burned off.

To protect the major portion of the two wheels 32 from the high temperature within the casing 40 and also to reduce the transfer of heat therefrom through the shaft 30 and to its supporting bearings, the principal portion of said sprocket 32, including the rings 98 and 99 and part of the ring 100 as well as the major portion of the shaft 30 within the housing 40, is embedded in a heavy drum 105 of insulating material which is preferably made up of sections which are split along a plane passing through the axis of the shaft 30, transversely of itself. The drum 105 is also made in sections, there being at least one transverse section between the two sprockets 32 and two sections, one outside each of said sprockets, these transverse sections being connected together with tie rods 106. Similar tie rods 106 or tie bolts not illustrated, may interconnect the sections of drum 105 along their plane of severance parallel the axis of shaft 30. The above described sprocket wheel is claimed in my divisional application, Serial No. 711,909, filed November 23, 1946, entitled "Sprocket wheel construction."

As clearly illustrated in Fig. 7 of the drawings, the end of the drum 105 is closely positioned with respect to the insulating material lining 107 of the head section 41 of casing 40. The opposite ends of head shaft 30 extend through close fitting openings in the side walls of the head section 41 and a stuffing box 108 is provided between each of said side walls and said shaft 30 which acts as a dirt and heat seal. A support for opposite ends of the shaft 30 is provided by a pair of self-aligning bearings, one of which is seen at 109. Said bearing 109 is preferably babbitt or bronze lined and is only semi-cylindrical in shape and supports the bottom portion of the shaft 30, since the load on the shaft 30 is always in a downward direction. The bearing 109 is enclosed and protected by the bearing box 29 which provides a lubrication well. Oil drip rings 110 are provided on shaft 30.

The structure of the bearing box 29 comprises an important contribution of my invention. In an elevator of the construction herein disclosed, due to the great height of the head shaft as well as the great weight on it, particularly when it is supporting the conveyor mechanism, it is extremely desirable to be able to renew the felt washers 111 which form the oil and dirt seal between the cylindrical openings on opposite sides of the bearing box 29 and the shaft 30 without requiring removal of said shaft 30 from the bearing 109. The bearing box 29 therefore includes a removable cap 112 which preferably receives an oil pipe 113. Oil is circulated through box 29 through pipe 113 and a drain pipe, not shown.

The bottom or fixed portion of the bearing box 29 is in the form of a main casting 114 which is rigidly attached to the I-beam 23, as

previously suggested. This casting 114 is provided on opposite sides with removable arcuate segments or portions 115 (see Figs. 7 and 11) which on their bottoms have tongues fitting in grooves formed in the cooperating arcuate portions of the casting 114.

By reference to Fig. 11 of the drawings, it will be seen that when the cap 112 is removed the arcuate segments or portions 115 may be rotated to remove them from the casting 114, whereupon they may be lifted from the shaft 30. When the parts are fully assembled, the felt washers 111 are received in continuous circular grooves, half of which is formed in a segment 115, the other half in an arcuate edge of cap 112. It is obvious, however, that when the cap 112 and the segments 115 are removed, the felt washers 111 may be readily removed, since they are originally cut to place them on the shaft 30 which can be freely done with the cap 112 and segment 115 removed. To reinsert a segment 115, the groove thereof is preferably fitted over the felt washer 111 with the segment on top of the shaft 30. The segment is then rotated with its tongue in the groove in the casting 114 until it reaches its normal position, as viewed in Figs. 7 and 11 of the drawings. Thereafter the cap 112 may be attached as by screws along the lateral edges thereof with the grooves thereof receiving the felt washer 111. The bearing and shaft assembly above described is claimed in my Patent No. 2,430,236, granted November 14, 1947, entitled "Bearing and shaft assembly."

As illustrated best in Fig. 2 of the drawings, it will be noted that one end of the shaft 30 is provided with a drive sprocket 116 which is keyed to the shaft 30 and at the other end it is provided with a brake wheel 117 with which mechanically operated brake device 118 (Fig. 1) cooperates. The drive sprocket 116 is driven from an appropriate motor and speed reducer mechanism 119 through an appropriate chain and sprocket or equivalent drive 120. The motor and speed reducing mechanism 119 is mounted on a platform formed on the rearward extending portions of the I-beams 23.

Another important feature of my invention resides in means for cooling or otherwise controlling the temperature of the head shaft 30 directly and by virtue of this fact cooling or controlling the temperature of the bearing 109 for said head shaft. This is of great importance due to the fact that in spite of all of the insulation provided, the head shaft 30 will become quite hot unless properly cooled. It is also because of the cooling of the shaft 30 and the consequent large temperature differential between it and the rim of wheel 32 that the above described special construction of said wheel 32 is required. To this end, the shaft 30 is provided with an axial bore 121 whereby it is formed as a hollow shaft. It will be understood that the cooling mechanism is duplicated at each end of the shaft 30. Extending into the bore 121 is a pipe 122, the outer periphery of which is spaced from the inner periphery of the bore 121. At its outer end the pipe 122 is provided with a fitting 123 which acts in the nature of a bearing. The fitting 123 is so constructed that a feed water elbow 124 connected thereto, will be effectively connected to the interior of the pipe 122 and a water discharge elbow 125 is effectively connected to a passage-way formed between the exterior of the pipe 122 and the cylindrical surface provided by the bore 121. The packing between the fitting 123 which

is stationary and the rotating shaft 30 is provided by packing ring 126 and associated packing gland 127 which is attached by screws to the end of the shaft 30. The fitting 123 is mounted on a stationary bracket 128 which may be connected to any desired closely associated portion of the main frame 20.

Adjacent its inner or right hand end, as viewed in Fig. 7, the pipe 122 is provided with radial holes 129 so as to provide communication between the feed and return paths for the cooling water or other temperature controlling fluid or medium. The inner end of the pipe 122 is provided with a rigidly attached plug 130 which is supported in the end of a filler and connecting cylindrical rod 131 which extends through the central portion of the shaft 30 and supports the inner ends of the pipes 122 associated with opposite ends of said shaft 30. It may be mentioned that axial movement of the pipes 122 is prevented since the fittings 123 to which said pipes in opposite ends of the shaft 30 are screw-threaded, are held by the above mentioned stationary brackets 128. Filler rod 131 is slightly smaller in diameter than the bore 121 and is pinned at its center to the shaft 30 for rotation therewith.

To provide a thorough scouring turbulent flow of water in its return path from the holes 129 to the discharge elbow 125, I provide wire helix 132 which is preferably rigidly attached to the exterior surface of the pipe 122 and is closely adjacent to the cylindrical surface of the bore 121, though slightly spaced from said surface, since the shaft 30 rotates while the wire helix 132 is stationary. It is evident that cooling water introduced by way of the feed elbow 124 will flow through the fitting 123 into the pipe 122 and out of the radial openings or holes 129 and thence will return by a greatly elongated and helical path of reduced cross-sectional area to provide what is known as "turbulent flow," during which it will scour the internal surface of the adjacent portion of the shaft 30 provided by the bore 121; ultimately flowing through the fitting 123 and the discharge elbow 125. This elongated helical path together with the scouring action will insure proper cooling of the shaft 30 and through it the bearing 109 so as to prevent burning out of said bearing and undue heating of the lubricating oil for it, which is within the bearing box 29. I also contemplate the use of the structure as above described for heating a shaft with a hot fluid or medium such as hot gas, air or water. This feature is disclosed and claimed in my divisional application, Serial No. 117,702, filed September 24, 1949, entitled Cooling means for elevator bearing shaft.

Attention is now directed particularly to Fig. 6 of the drawings and to the structure of the foot shaft assembly 38 and the mechanism for mounting the foot shaft 37 for vertical adjustment in the slots 52. The structure illustrated in Fig. 6 is duplicated on each side of the unit.

The foot shaft assembly 38 includes at each side a traction wheel 39, the structure of which is illustrated in detail in Figs. 6 and 9 of the drawings. Said wheel 39 includes a hub 133 and a plain ring type rim 134, the hub and rim being split, the former being assembled and clamped to the shaft 37 by a pair of elongated bolts 135, the sections of rim 134 being connected by spaced bolts 136. Interconnecting the hub 133 and rim 134 is a plurality of yoke type spokes 137. It is to be noted that all of the spokes 137 extend from

the hub 133 to the rim 134 in a similar manner and each is offset from the radial to provide for relative expansion between the hub 133 and the rim 134. To aid in this expansion the opposite ends of each spoke 137 are pivotally attached to the hub 133 and rim 134 by rivets 138 and 139, respectively. It is evident that if the ring 134 should expand under the influence of the heat in the casing 40 it will be free to do so and the spokes 137 will swing about their pivot points and move toward a radial position. Conversely, should the rim 134 contract, the spokes 137 would move farther away from the radial position.

The construction provided is such as to compensate readily for wide temperature variations to which the wheel 39 is subjected, and to take care of the fact that shaft 37 is cooled while the rim 134 is very hot while the conveyor is in operation. The hub 133 and the major portion of each of the spokes 137 are embedded in a drum of insulating material 160 which is built up of a plurality of axially separable sections held together by longitudinal tie bolts 161. The drum 140 is also split along a plane passing through the axis of shaft 37, the parts being held together by tie bolts not shown. The insulating material which is between the spokes 137 may be plastic in form when the foot shaft assembly 38 is originally assembled and it will become hard under the influence of the heat to which it is subjected. Each end of the shaft 37 extends through a round hole in the insulation plate 60 and the attached steel plate 61, as previously described, and a stuffing box 142 is attached to the plate 61 which provides a seal between said shaft 37 and said steel plate 61 adjacent this opening. Each end of shaft 37 is also supported in a journal bearing 143 which is of the totally enclosed type and which is mounted in a beam 144. The two beams 144 on opposite sides of the casing 40 are preferably placed inside the main frame 20 and constitute the two side members of a box like frame 145 (see Fig. 1) the structure of which is described more completely hereinafter.

Mechanism is provided for cooling each of the bearings 143 which is generally similar in structure to that above described in connection with bearing boxes 29. That is, the shaft 37 is hollow and there is a fitting 146 adjacent each end thereof which is received in a collar 147 clamped to the shaft 37, there being a packing ring and associated packing gland 148 to provide a water seal between the cylindrical outer surface of the fitting 146 and the collar 147, as well as with the rotating shaft 37. The fitting 146 is stationary and is supported by a bracket 149 which is connected to the beam 144. Connected to the fitting 146 is a pipe 150 the outside surface of which is spaced inwardly from the bore 151 of the hollow shaft 37. Cooling water feed elbow 152 is connected through fitting 146 to the interior of pipe 150 and water discharge elbow 153 is connected by fitting 146 to the passageway formed on the outside of the pipe 150 and the surface of bore 151. The two pipes 150 which extend from opposite sides of the assembly 38 are connected together and this construction is slightly different from that of the assembly 31 in that a pipe 154 telescopes with the two pipes 150 and is riveted to them. This pipe 154 is provided with radial bores 155 providing ports to permit the feed water on the interior of the pipes 150 to flow outwardly into the return passageways between the outside of pipes 150 and the inside of hollow shaft 37. A brass helix 156 surrounds each pipe 150 and is

rigidly attached thereto and spaced a very small amount from the wall of bore 151 to provide an elongated helical path for the cooling water, causing it to scour the interior surface of the hollow shaft 37 and thus to cool it. It is to be noted that the cooling path of this foot shaft 37 extends appreciably into the assembly 38 and consequently the interior thereof will be cooled to a greater extent than the interior of the head shaft assembly 31. This difference is provided because it is desired to cool the foot wheels 39 as much as possible as their construction provides for considerable expansion and contraction of the rim 134. On the other hand, it is not desired to cool the sprocket wheel 32 to any great extent to cause such a temperature differential between inner plate 98 and the outer ring 100. It is to be understood, however, that if desired the head sprockets may follow the general construction of the foot wheels 39 by providing teeth on the rims thereof and under such conditions if it is desired, the cooling arrangement illustrated for the foot shaft may be employed for the head shaft. Conversely, the head shaft and associated parts may be employed for the foot shaft.

Attention is now directed particularly to Fig. 1 of the drawings and to the construction which provides for the floating vertical relation of the foot shaft assembly 38. The boxlike frame 145 is pivotally mounted at its rear on two pivot points one of which is seen at 157, said pivots 157 being mounted on rollers which roll between the top and bottom guides 158. As a consequence, as the frame 145 pivots about said pivots 157 they move in a horizontal plane to provide for vertical or rectilinear instead of arcuate travel of the shaft 37. It is, of course, evident that the axis of pivots 157 is parallel with the axis of shaft 37. It is also desirable to indicate the position of the frame 145 and, as a consequence, of the shaft 37 in a slot 52. To this end one of the frame beams is provided with a pointer 159 which cooperates with a stationary scale 16 attached to the main frame 20 and indicates directly the position of the frame 145. It is, of course, obvious that in view of the great height of the elevator or conveyor there will be an exceedingly heavy load on the head shaft 30 and on the links of chains 33 at the upper ends since they must support the weight of substantially the entire conveyor mechanism 34. In order not to increase this load further, the frame 145 and the foot shaft assembly 38 is substantially counterbalanced by means of a counterbalancing weight 161 preferably mounted in a housing 162 and suspended from one or more cables 163 which is reeved over a pulley 164 which may be hooked to any frame structure and attached to a double diameter drum 165. One or more suspension cables or rods 166 extend from the small diameter of the drum 165 to the free end of the frame 145. The double cylindrical drum 165 operates as a moment multiplier to reduce the necessary weight of the counterbalancing weight 161. The structure 60 above described that provides for vertical floating of the foot shaft assembly 38 and for indicating its position is claimed in my divisional application, Serial No. 711,910, filed November 23, 1946, for a "Conveyor shaft counterbalancing and indicating apparatus."

In the operation of the device comprising my invention, the hot material such as clay or fuller's earth is fed to the feed chute 48 and by it directly into the buckets 35 as they travel upwardly 75 from the foot shaft assembly 38 along their work-

ing or elevating run. As the buckets 35 travel over the head shaft assembly 34 they discharge onto the discharge chute 42, some of the material being first received by the auxiliary discharge chute 43. The draft chains 33 are guided through the totally enclosing and insulating housing 40 by the sectional guides 80, the insulated casing or housing being made up of individual panels, individually suspended from the main frame 20 and is free to contract or expand under variations in temperature and variations in atmospheric conditions including wind and rain.

In case of a shut down when it is desirable to cool out the interior of casing or housing 40 the exhaust door 45 at the top or head section 44 is opened and the draft door 49 is opened producing a draft through the casing 40 by virtue of the temperature therein. In view of the high temperature within the housing or casing 40, which may be as high as 1000 degrees Fahrenheit, provision has been made for cooling the bearings and associated portions of the head and foot shafts 30 and 37, respectively.

While provision has been made for the free vertical movement of the foot shaft, which may be caused by differences in temperature within the housing or casing 40, this has been accomplished by providing a heat and dust seal adjacent the foot shaft 37. Furthermore, both the head sprocket wheels and the foot wheels for the two strands of chain 33 have been especially constructed to take care of differences in temperature adjacent the outer rims thereof as compared with the hubs or portions thereof attached to their respective shafts. Structure of the head and foot wheels is described and claimed in my co-pending application Serial No. 607,115, filed July 26, 1945, entitled "Wheel construction." The casing or housing construction is fully insulated. Furthermore, the housing 40 is relieved of all functions as a main frame and an entirely separate structural tower or main frame is provided. Furthermore, the panel construction of the housing or casing 40 provides for expansion and contraction thereof under varying internal temperatures and external atmospheric conditions.

Obviously those skilled in the art may make various changes in the details and arrangement of parts without departing from the spirit and scope of the invention as defined by the claims hereto appended, and I wish therefore not to be restricted to the precise construction herein disclosed.

Having thus described and shown an embodiment of my invention, what I now desire to secure by Letters Patent of the United States is:

1. In an elevator adapted to operate at temperatures varying widely from the ambient temperatures, the combination with a structural main frame, of conveyor mechanism in said frame, a housing for said conveyor mechanism formed of separate insulated panels, one above the other, and separated conveyor guide means on separate panels in vertical alignment to guide the conveyor mechanism while providing for vertical movement of said guides relative to each other in response to differences in expansion and contraction of said main frame and panels.

2. In an elevator adapted to operate at temperatures varying widely from the ambient temperatures, the combination with a structural main frame, of conveyor mechanism in said frame, a housing for said conveyor mechanism formed of

separate insulated panels, one above the other, and separated conveyor guide means on separate panels in alignment to guide the conveyor mechanism while providing for vertical movement of said panels relative to each other in response to differences in expansion and contraction of said main frame and panels.

3. In an elevator adapted to operate at temperatures varying widely from the ambient temperature, the combination of a structural support, a housing carried by said structural support having opposite side walls adapted to compensate for expansion without materially increasing their overall lengths, each of said walls including a plurality of panels, means rigidly mounting each of said panels in a local area thereof, conveyor mechanism within said housing, separate aligned conveyor guide means carried by each of said opposite walls, each of said guide means including separate guide members, insulation secured to and substantially covering the inside faces of each of said panels, and means extending through said insulation securing said guide members to said panels whereby said guide members may move relative to each other and to said panels in response to expansion and contraction of the panels.

4. In an elevator adapted to operate at temperatures varying widely from the ambient temperature, the combination of a structural support, a housing carried by said structural support having opposite side walls adapted to compensate for expansion without materially increasing their overall lengths, each of said walls including a plurality of panels, means rigidly mounting each of said panels in a local area thereof, conveyor mechanism within said housing, separate aligned conveyor guide means carried by each of said opposite walls, each of said guide means including separate guide members, and means securing said guide members to said panels whereby said guide members may move relative to each other and to said panels in response to expansion and contraction of the panels.

5. A conveyor housing including head and foot sections, housing structure connecting said head and foot sections including four upwardly extending main frame members one at each corner of a rectangle, means forming circumferential belts connecting said main frame members together in substantially horizontal spaced planes, each of said belt means including four plates, opposite plates of which form moment connectors and are connected at opposite ends to main frame members, and other opposite plates of which are spaced inwardly of said main frame members and are connected at their ends to said moment connectors, tubes extending between pairs of adjacent of said belts, means rigidly securing the top of each of said tubes to one of said belts, and means slidably interconnecting the bottoms of said tubes to their adjacent belts, said tubes and belts cooperating to form a casing connecting said head and foot sections wherein each tubular section of the casing may expand and contract independently of the other sections without changing the overall length of the casing.

6. A conveyor housing including a main frame having four upwardly extending spaced apart main frame members, one at each corner of a rectangle, belt means connecting said main frame members rigidly together in a substantially horizontal plane, said belt means including four plates opposite plates of which are rigidly con-

nected at opposite ends to main frame members and other opposite plates of which are spaced inwardly of said main frame members and are rigidly connected at their ends to said first named plates, a relatively long tubular casing having walls extending substantially in the planes of the belt plates, and means securing said relatively long tubular casing to said belt means whereby said relatively long casing is supported by said belt means and expansion and contraction of said casing relative to said frame resulting from a differential between their temperatures may occur.

7. A conveyor housing including a main frame having four upwardly extending spaced apart main frame members, one at each corner of a rectangle, means forming belts connecting said main frame members rigidly together in substantially horizontal spaced planes, each of said belt means including four plates opposite plates of which are rigidly connected at opposite ends to main frame members and other opposite plates of which are spaced inwardly of said main frame members and are rigidly connected at their ends to said first named pairs of plates, a plurality of relatively long tubular casing sections interconnecting adjacent of said belts and co-operating to form a conveyor casing extending substantially in the planes of said belt plates, means rigidly connecting each of said tubular sections at one end thereof to one of said belts, and means slidably interconnecting the opposite end of each of said tubular sections to an adjacent belt whereby each of said tubular sections is rigidly supported by one of said belts and said casing is free to expand and contract in sections between said belts while its overall length remains substantially constant.

8. A conveyor housing including a main frame having four upwardly extending spaced apart main frame members, one at each corner of a rectangle, means forming belts connecting said main frame members rigidly together in substantially horizontal spaced planes, each of said belt means including four plates opposite plates of which are rigidly connected at opposite ends to main frame members and other opposite plates of which are spaced inwardly of said main frame members and are rigidly connected at their ends to said first named plates, a plurality of relatively long tubular casing sections interconnecting adjacent of said belts and co-operating to form a conveyor casing extending substantially in the planes of the belt plates, each of said tubular casing sections including means forming four separate side panels, means locally rigidly connecting each of said side panels at one end thereof to one of said belts, and means slidably interconnecting the opposite end of each of said side panels to an adjacent belt whereby each of said separate panels is rigidly supported by one of said belts and said casing is free to expand and contract in sections between said belts while its overall length remains substantially constant.

9. A conveyor housing including a main frame having four upwardly extending spaced apart main frame members, one at each corner of a rectangle, means forming belts connecting said main frame members rigidly together in substantially horizontal spaced planes, each of said belt means including four plates opposite plates of which are rigidly connected at opposite ends to main frame members and other opposite plates of which are spaced inwardly of said main frame

members and are rigidly connected at their ends to said first named plates, a plurality of relatively long tubular casing sections interconnecting adjacent of said belts and co-operating to form a conveyor casing extending substantially in the planes of the belt plates, each of said tubular casing sections including means forming four separate side panels, insulation attached to each of said separate side panels, means locally rigidly connecting each of said side panels at one end thereof to one of said belts, and means slidably interconnecting the opposite end of each of said side panels to an adjacent belt whereby each of said separate panels is rigidly supported by one of said belts and said casing is free to expand and contract in sections between said belts while its overall length remains substantially constant.

10. An elevator conveyor including an upstanding main frame including spaced apart upstanding frame members, laterally extending means rigidly connecting said frame members, an enclosing casing located generally between said upstanding frame members adapted to enclose conveyor mechanism including a circumferential belt disposed in a horizontal plane which forms part of said casing and part of said frame, and means rigidly connecting said belt and said upstanding frame, said enclosing casing also including casing means hanging down from said belt and connected at its top thereto, said hanging casing means being thereby suspended solely from said belt.

STANLEY M. MERCIER.
